 Lindberg Trust, Cleveland, Ohio, a trust of
 Ohio

Application May 3, 1950, Serial No. 159,673

8 Claims. (Cl. 103—126)

1

This invention relates to pressure fluid gear pumps and has for one of its primary objects to provide an improved gear pump of simplified construction and increased efficiency.

Another object is to provide a construction for automatically maintaining pressure responsive longitudinally floating bearing bushings in sealed contact with the side faces of the associated gears.

Another object is to provide an improved fluid pressure loaded floating end bushing construction which is also self-sealing with respect to the pump housing.

Another object is to provide an improved floating end bearing construction which is in the form of an elongated one-piece straight wall bushing to engage both adjacent journals of the two gears and fill up the pump housing cavity so as to be a single self-sealing bushing that necessitates no sealing accessories.

Another object is to provide such a one-piece floating end bushing with a pressure responsive sliding means for automatically maintaining proper pressure loading and alignment and sealing of the bushing with the gear faces and the pump housing.

Another object is to provide such a one-piece floating end bushing and single pressure pin loading device therefor that will maintain proper pressure loading, alignment and sealing and avoid cocking and which bushing may support the gear journals as a plain bushing or have rolling bearing elements therein to support the gear journals.

With the foregoing and other objects in view, the invention resides in the combination of parts and in the details of construction hereinafter set forth in the following specification and appended claims, certain embodiments thereof being illustrated in the accompanying drawings, in which:

Figure 1 is a view in elevation of the pressure inlet and outlet end of the fluid pressure gear pump;

Figure 2 is a top plan view of the pump;

Figure 3 is a view in section taken through the pump along line 3—3 of Figure 1;

Figure 4 is a view partly in top elevation and partly in transverse section of the pump;

Figure 5 is a view in section taken along line 5—5 of Figure 4;

Figure 6 is a view similar to Figure 3, showing the gear journals supported by needle bearings in the bushings;

Figure 7 is a view in perspective of one of the gear journal bushings; and

2

Figure 8 is a view in section taken along line 8—8 of Figure 6.

Referring more particularly to the drawings, the main gear pump housing 1 has secured thereto by bolts 2 a housing 3 for the fluid inlet 4 and outlet 5.

The pump is shown to comprise two pump gears 6 and 7 with meshing teeth 8 and 9. On opposite sides of teeth 8, gear 6 is provided with journals 10 and 11 and on opposite sides of teeth 9, gear 7 is provided with journals 12 and 13. Journal 11 of gear 6 and journal 13 of gear 7 are mounted to rotate in an elongated unflanged one-piece straight side bushing 14 which is mounted to be longitudinally slidable on the inner surface of housing member 15 and which fills up the housing cavity. Such a bushing 14 is shown in perspective in Figure 7. Journal 10 of gear 6 and journal 12 of gear 7 are mounted to rotate in a similar elongated unflanged one-piece straight side bushing 16 that is likewise mounted to be longitudinally slidable on the inner surface of the housing and likewise fills up the housing cavity. The opposed faces 17 and 18 of bushings 14 and 16 are pressure loaded to engage the opposite side faces of gear teeth 8 of gear 6 in fluid sealing relationship, and the opposed faces 19 and 20 of bushings 14 and 16 are pressure loaded to engage the opposite side faces of gear teeth 9 of gear 7 in fluid sealing relationship. Gears 6 and 7 are provided with longitudinal bores 21 and 22.

Journal 10 of gear 6 has a reduced extension 23 that is splined to a coupling member 24 having a flange 25 that engages with a bearing ring 35, the opposite side of which presses against a flexible seal ring 27, that, in turn, presses against a collar 28 provided with an annular seal ring 29 between it and the housing and secured therein by a snap ring 30. Coupling member 24 is secured by pin 31 to the splined gear connector 32. A compression coil spring 33, bearing inwardly against gear journal 10 is provided to eliminate end play of gear 6 and affecting the seal assembly at this end of the gear.

Housings 1 and 3 when connected together are fluid sealed by rings 34 and 35. The fluid from inlet 4 passes through inlet chamber 36 to gear 7 and from gear 6 the fluid passes through outlet passage 37 to outlet 5.

Mounted in housing 3 is a spring and pressure loaded slidable pin 38 provided with an annular seal ring 39. It is normally urged by a compression coil spring 40 in the recessed head of the plug to initially resiliently force the one-piece gear bushing 14 to the left, as viewed in

Figure 4, which leaves an axial chamber 41 between the housing 3 and bushing 14.

Fluid pressure is fed in from the high pressure side from passage 37 through passage 48 in behind and in the recessed head of floating pin 38 to force the pin 38 to the left to fluid pressure load the bushing 14. Pressure loaded pin 38 is located approximately opposite the center of internal pressure and on the horizontal centerline, but displaced outwardly from the vertical centerline, as shown in dotted lines in Figure 8. The resulting action of pressure fluid from the high pressure, or discharge, side on the pin 38 is to pressure load the bushings. Pressure fluid in space 50 behind bushing 16 and behind spring 33 is vented through passage 51 and bore 21 to space 41 behind bushing 14.

Housing 3 is provided with a bore 42 to receive a retaining plug 43 and a coil spring 44, urging a ball valve 45 to normally close passage 46 that communicates with passage 47 leading to axial chamber 41. This provides a low pressure relief valve for venting chamber 41 to low pressure through passage 49 to the inlet passage 36.

The one-piece floating bushings 14 and 16 not only completely fill the housing cavities, but are also elongated and straight sided with no flanges. The intimate contact of their outer surfaces throughout their entire lengths with the inner surface of the housing provides for an effective seal against fluid leakage. They are thus self-sealing and require no additional sealing accessories. Another advantage of this one-piece floating bushing construction lies in the fact that it is self-aligning with respect to the gear journals, the gear faces and the housing, with virtually no tendency to cock in their pressure responsive sliding movements. This latter is especially true because the single bushing 14 is pressure loaded by the single pressure loaded pin 38 which is located approximately opposite the center of internal pressure.

In my gear pump construction, I have considerably reduced the number of essential operating parts. By reason of employing single one-piece straight sided floating bushings, I am able to employ a slidable pressure pin, or piston, 38 for effectively pressure loading the bushing 14 by applying the fluid pressure from the high pressure side to the pin 38. Moreover, in such a construction I find it unnecessary to employ insert plugs to insure against leakage. The fluid that accumulates in space 41, upon movement of bushing 14, is readily vented past the low pressure ball check valve to the low pressure side. Thus I find it unnecessary to provide any relief recesses between the side faces of the gears and the bushings.

All of this is in contrast to conventional gear pumps employing separate pressure loaded bushings for each journal of each gear in which case it is necessary to use rubber inserts as fluid seals. Such inserts are placed in drilled holes on the low pressure side connecting the flats of both the adjacent floating bushings and the pump housing to keep the high pressure in chambers behind the bushings from by-passing directly to the pump inlet. Failure of such rubber inserts results in failure of the pump. Conventional pumps also employ reliefs on the faces of the flanges of the floating bushings as a means for controlling the magnitude of the pressure loading. Conventional gear pump construction, moreover, precludes the use of rolling bearing elements, such as ball, roller or needle bearings, inasmuch

as the cocking tendency of the bushings employed for each journal of each gear results in an overload on the bearing elements.

Due to the nature of my construction, however, I may employ plain bushings, as described, or I may also employ rolling bearing elements carried by the bushings to support the gear journals. I have shown such an arrangement in Figure 6, in which the general overall construction 10 remains the same as previously described, with the exception that I have shown needle bearings 52 carried by bushing 14 to support journal 11 of gear 6 and needle bearings 53, also carried by the same bushing 14 to support journal 13 of gear 7. Likewise, I have shown needle bearings 54 carried by bushing 16 to support journal 10 of gear 6 and needle bearings 55 carried by the same bushing 16 to support journal 12 of gear 7.

While I have described as a preferred embodiment of my invention the use of a single pressure responsive floating pin 38 for pressure loading the one-piece bushing 14, in some instances it may be desirable to employ more than one of such pins when it is desired to more evenly distribute the pressure loading force across the back face of the sliding bushing 14 when the latter is of larger sizes in larger gear pumps.

I claim:

1. A gear type pump comprising a hollow housing having a fluid inlet and outlet, said housing having a gear chamber and an auxiliary chamber in said housing between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidable in contact with the inner surface of said hollow housing, said bushing being arranged axially of the adjacent axial faces of both of said gear members, said bushing surrounding and supporting the adjacent parallel journals of both of said gears and having a front axial face cooperable with the adjacent axial face of its associated gear members to provide a seal between said bushing and said gear members and a piston slidably mounted in said auxiliary chamber in said hollow housing and in axial contact with the back face of said bushing and a fluid passage leading from the pump discharge outlet to said auxiliary chamber on the back face of said piston to provide a fluid pressure loading on the back of said bushing to urge said bushing against said gears.

2. A gear type pump comprising a hollow housing having a fluid inlet and outlet, said housing having a gear chamber and an auxiliary chamber in said housing between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidable in contact with the inner surface of said hollow housing, said bushing being arranged axially of the adjacent axial faces of both of said gear members, said bushing surrounding and supporting the adjacent parallel journals of both of said gears and having a front axial face cooperable

with the adjacent axial face of both of its associated adjacent gear members to provide a seal between said bushing and said gear members, a piston slidably mounted in said auxiliary chamber in said hollow housing, said auxiliary chamber being axially removed from said bushing, said piston being in axial contact with the back face of said bushing and a fluid passage leading from the pump discharge outlet to said auxiliary chamber on the back face of said piston to provide a fluid pressure loading on the back face of said bushing to urge said bushing against said gears.

3. A gear type pump comprising a hollow housing having a fluid inlet and outlet, said housing having a gear chamber and an auxiliary chamber in said housing between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidable in contact with the inner surface of said hollow housing, said bushing being arranged axially of the adjacent axial faces of both of said gear members, said bushing surrounding and supporting the adjacent parallel journals of both of said gears and having a front axial face cooperable with the adjacent axial face of its associated adjacent gear members to provide a seal between said bushing and said gear members, a piston slidably mounted in said auxiliary chamber in said hollow housing, said auxiliary chamber being axially removed from said bushing and of greater axial length than said piston, said piston being in contact with the back face of said bushing and a fluid passage leading from the pump discharge outlet to said auxiliary chamber on the back face of said piston to provide a fluid pressure loading on the back face of said bushing to urge said bushing against said gears.

4. A gear type pump comprising a hollow housing having a liquid inlet and outlet, said housing having a gear chamber and an auxiliary chamber in said housing between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidable in contact with the inner surface of said hollow housing, said bushing being arranged axially of the adjacent axial faces of both of said gear members, said bushing surrounding and supporting the adjacent parallel journals of both of said gears and having a front axial face cooperable with the adjacent axial faces of both of said gear members to provide a seal between said bushing and said gear members, a piston slidably mounted in said auxiliary chamber in said hollow housing, said auxiliary chamber being axially removed from said bushing and of greater axial length than said piston, said piston being in contact with the back face of said bushing to urge said bushing against said gears, a liquid passage leading from the pump discharge outlet to said auxiliary chamber on the back face of said piston to provide a liquid pressure loading on the back face of said bushing and venting means for venting

liquid from any space between said bushing and said gear journals and between said bushing and said housing to the low pressure inlet side of said pump.

5. A gear type pump comprising a hollow housing having a liquid inlet and outlet, said housing having a gear chamber and an auxiliary chamber in said housing between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidable in contact with the inner surface of said hollow housing, said bushing being arranged axially of the adjacent axial faces of both of said gear members, said bushing surrounding and supporting the adjacent parallel journals of both of said gears and having a front axial face cooperable with the adjacent axial faces of both of said gear members to provide a seal between said bushing and said gear members and a piston slidably mounted in said auxiliary chamber in said hollow housing, said auxiliary chamber being axially removed from said bushing and of greater axial length than said piston, said piston being in contact with the back face of said bushing to urge said bushing against said gears, a liquid passage leading from the pump discharge outlet to said auxiliary chamber on the back face of said piston to provide a liquid pressure loading on the back face of said bushing and venting means, including a low pressure relief valve therein, for venting liquid from any space between said bushing and said gear journals and between said bushing and said housing to the low pressure inlet side of said pump.

6. A gear type pump comprising a hollow housing having a fluid inlet and outlet, said housing having a gear chamber and an auxiliary chamber in said housing between said gear chamber and said outlet, a pair of meshing gear members mounted in said gear chamber, each of said gear members having journals extending from the opposite faces thereof, a pair of unflanged elongated one-piece bushings, each having a flat front and back end face, each bushing having straight side walls connected by curved ends, each bushing being mounted to have its entire periphery longitudinally slidable in contact with the inner surface of said hollow housing, said bushings being arranged one on each side of said pair of gear members and axially adjacent the two opposite axial faces of both of said gear members, each of said bushings surrounding and supporting the adjacent parallel journals of both of said gears and having a front axial face cooperable with the adjacent axial face of its associated gear members to provide a seal between said bushings and said gear members and a piston slidably mounted in said auxiliary chamber in said hollow housing and in axial contact with the back face of one of said bushing members and a fluid passage leading from the pump discharge outlet to said piston to provide a fluid pressure loading on the back face of said last named bushing.

7. A gear type pump comprising a hollow housing having a fluid inlet and outlet, said housing having a gear chamber and an auxiliary chamber in said housing between said gear chamber and said outlet, a pair of meshing gear members mounted in said gear chamber, each of said gear

members having journals extending from the opposite faces thereof, a pair of unflanged, elongated one-piece bushings, each having a flat front and back end face, each of said bushings having straight side walls connected by curved ends, each bushing being mounted to have its entire periphery longitudinally slidably in contact with the inner surface of said hollow housing, said bushings being arranged one on each side of said pair of gear members, and axially adjacent the two opposite axial faces of both of said gear members, each of said bushings surrounding and supporting the adjacent parallel journals of both of said gears and having a front axial face cooperable with the adjacent axial face of its associated gear member to provide a seal between said bushings and said gear members, a piston slidably mounted in said auxiliary chamber in said hollow housing and in contact with the back face of one of said bushings to urge the same against said gears, said auxiliary chamber being axially removed from one of said bushings and of greater axial length than said piston, and a fluid passage leading from the pump discharge outlet to said auxiliary chamber on the back face of said piston to provide a fluid pressure loading on the back face of said bushing;

8. A gear type pump comprising a hollow housing having a fluid inlet and outlet, said housing having a gear chamber and an auxiliary chamber in said housing and between said gear chamber and said outlet, a pair of meshing gear members mounted in said gear chamber, each of said gear members having journals extending from the opposite faces thereof, an elongated one-piece bushing having flat front and back end faces, said bushing having straight side walls connected by curved ends, said bushing being mounted to have its entire periphery longitudinally slidably in contact with the inner surface of said hollow housing and in contact with the back face of said piston to provide a fluid pressure loading on the back face of said bushing;

5 housing, said bushing being arranged axially of the adjacent axial faces of both of said gear members, said bushing surrounding and supporting the adjacent parallel journals of both of said gears and having a front axial face cooperable with the adjacent axial face of its associated gear member to provide a seal between said bushing and said gear members, said auxiliary chamber being axially removed from said bushing and a spring urged piston slidably mounted in said auxiliary chamber and located transversely away from the center line between the curved ends of said bushing and toward said pump discharge outlet, and in axial contact with the back face of said bushing; 15 and a fluid passage leading from the pump discharge outlet to said auxiliary chamber on the back face of said piston to provide a fluid pressure loading on the back face of said bushing in a direction substantially opposite the center of internal pump pressure.
